UNITED STATES PATENT OFFICE.

CARL S. NORDEN, OF HAVERHILL, MASSACHUSETTS.

SHOE-RIPPING MACHINE.

1,410,590.

Specification of Letters Patent. Patented Mar. 28, 1922.

Application filed March 13, 1920. Serial No. 365,434.

To all whom it may concern:

Be it known that I, CARL S. NORDEN, a citizen of the United States, and a resident of Haverhill, county of Essex, State of Massachusetts, have invented an Improvement 5 in Shoe-Ripping Machines, of which the following is a specification.

In the manufacture of shoes it occasionally happens that the upper is torn, or otherwise damaged beyond repair, so that all that 10 can be done with it is to rip it apart and use undamaged portions for other shoes.

Usually soles of such shoes can be used again provided the stitches which connect it 15 to the upper are cut or removed, so that the upper may be separated from the sole.

To do this with a hand knife, without injury to the sole, is a slow process and with some shoes it cannot be done in this manner, 20 on account of the fact that metal fasteners are employed.

In the manufacture of shoes, it is frequently necessary to remove loose or ragged portions of the soles which are frequently 25 present on the flesh side, the common practice being to remove such portions with a hand knife, this operation being known as "fleshing."

The objects of my invention are to provide 30 a machine of simple design which is adapted to perform the operation of cutting the stitches, or other fastening means between the upper and sole of a shoe, so that the upper may be readily separated from the 35 sole, also to provide a machine which may be readily adapted to cut different forms of upper fastening means, including those which are wire fastened, and which may be further adapted to perform the fleshing operation 40 on soles above referred to.

I accomplish these objects primarily by providing a machine having in combination with a single feed roll for the tread face of the sole, a knife which is movable transversely of the direction of the feed, so that the cutting operation may be performed without substantial opposition to the feeding action.

Preferred embodiments of the invention 50 are shown in the accompanying drawings in which:—

Figs. 1 and 2 are, respectively, a plan and an end elevation of a machine embodying my invention.

Fig. 3 is a sectional view at line 3—3 of Fig. 1.

Fig. 4 is a detail plan view of one form of cutter which I employ.

Fig. 5 is a sectional view, similar to Fig. 3, illustrating the manner of use of the machine for sole fleshing.

Figs. 6 to 11 are detail plan and sectional views of modified forms of cutters which are employed for different classes of work.

As shown in the drawings, the machine 65 comprises two side frames 10, having a main shaft 12 journaled therein at the rear ends thereof, said shaft being adapted to be constantly driven. A feed roll 14, which is covered with corrugated rubber, or some other 70 suitable frictional material, which will not damage the grain surface of a sole, is journaled in the front end of said frames and is arranged to be driven from the main shaft by intermediate gears 16, 18 and 20, so that 75 the movement thereof above its axis is to the rear, as indicated in Fig. 2.

A guard plate 22 is arranged to extend from one side frame to the other, and is provided with ears 23 at its ends through which 80 horizontally disposed pivots 24 extend, said pivots being mounted in blocks 26, which are held in guideways 27 on the side frames, and said blocks being pressed downwardly by springs 28. Vertical movement of the 85 rear portion of the plate 22 is thus permitted by the yielding of the springs 28, and to permit yielding to a greater extent at one end than at the other, the pivots are made to fit somewhat loosely in the blocks 26 and 90 the latter are made to fit somewhat loosely in their guideways.

A guide plate 30 is secured to the plate 22, by screws 33, or other suitable means and said plates have oppositely disposed grooves 95 formed therein, in which a knife 32 is arranged to slide therebetween, said knife having longitudinal slots through which guide pins 31 pass, said pins being fixed in plate 22. A cam 34 is secured on the end of the 100 main shaft 12 and a cam lever 36 is mounted to swing on a pivot 38 at an intermediate point, said lever being engaged at one end in the groove of the cam 34 and at the other end being connected to the knife 32 by a link 105 40, said link having a ball and socket, or some other suitable form of universal joint connection, with said lever, at one end, and with the knife at the other, whereby, when the main shaft is driven the knife will be reciprocated.

Said knife 32 is so arranged between the

plates 22 and 30 that its cutting edge extends beyond the edges of the plates for a sufficient distance to enable the same to operate, as hereafter explained.

- 5 The under side of the plate 22 is bevelled from its front edge to form a work-engaging face 22^a, and the plate is so arranged with relation to the roll 14 that its face 22^a will be moved into close proximity to the 10 roll surface closely adjacent its front edge, when swung downward to its fullest extent, as indicated in Fig. 2.

A coil spring 42 is attached to plate 22 in position to draw the same towards the roll 15 and an arm 43 is also connected to said plate in such a position that, when it is pressed, or drawn down, the plates 22 and 30 and knife therebetween will be swung upward.

If it is desired, for example, to remove the 20 upper from the sole of a turn shoe, the arm 44 is depressed to raise the plate 22 sufficiently to permit the end of the sole to be inserted beneath it, while the tread surface of the sole rests on the surface of the roll.

25 In this position the seam which connects the sole and upper will, by the feeding action of the roll, be pressed against the knife edge, and, as the knife will be rapidly reciprocating it will make a drawing cut on 30 the stitches with which it is engaged and thus cut the same, without substantial resistance to the feeding action on the shoe, by the frictional engagement of the roll or by the operator in pushing the shoe against the 35 knife.

While this operation is taking place, the face 22^a of the plate 22 will rest on the upper surface of the sole and act to prevent the knife from cutting into the sole while the 40 upper plate 30 will act to support the upper as it is cut away from the sole, as indicated in Fig. 3.

The upper will thus be rapidly severed from the sole, as the shoe is passed over the 45 roll.

In case of unevenness in the sole which cannot be compensated for by the up and down swinging movement of the knife, the latter will be permitted to tilt upward at 50 either end by the bodily movement of the pivots 24 against the action of the springs 28, which movement is permitted without interfering with the reciprocating action of the knife, which is adapted to be driven in 55 the different positions in which it is held.

While the form of knife above described will be suitable for cutting thread, it is not suitable where metal fasteners are employed, as in certain forms of McKay shoes, in 60 which case I preferably employ the construction of Figs. 8, 9 and 19, in which the plate 44, otherwise corresponding in all particulars to the plate 22, already described, is provided with a series of sharp edged, 65 pointed, or tapering fingers 44^a, at its front

edge, and a knife 46, (corresponding to the knife 32) is also provided with sharp edged teeth 46^a formed to have a shearing action with the fingers 44^a, a top plate 48, similar to the plate 30, is secured on the plate 44 by 70 screws 49, the front edge of said plate 48 terminating so as to expose the end portions of the teeth 46^a, the latter also extending beyond the ends of the fingers 44^a to approximately the same extent that they extend beyond the edge of the guard plate 48, as indicated in Fig. 10.

This form of cutter will not only perform the work of the cutter first described, but will also cut fasteners of small wire such as 80 are employed in certain kinds of shoes, the manner of operation in removing the upper from the soles with this form of cutter, is the same as that already described, except that the knife makes a positive shearing cut, 85 instead of a drawing cut, in severing the fastenings.

By a further modification in the form of cutter, the machine may be adapted for the work of fleshing soles, and, for this purpose, 90 a form of cutter is employed, which is similar to the form last described, but differing therefrom in certain details now to be described.

As shown in Figs. 5, 6, 7 and 11, the cutter comprises an underplate 50, similar in form to the plate 44, but having shearing fingers 50^a, which are of somewhat greater length than the fingers 44^a which taper to slightly blunt or dull points, and a knife 100 52, which is similar to knife 46, except that its teeth 52^a, which operate in shearing relation to the fingers 50^a, do not extend beyond the ends of said fingers, but terminate slightly short of the ends thereof. The 105 knife 52 is held in position by screws 54, which pass through slots in the knife and are secured in the under plate 50. The relative arrangement of the roll and cutter is such that the under sides of the fingers 50^a, 110 close to their ends, may rest on the feed roll.

When a sole is to be fleshed, it is inserted beneath the cutter, in a manner similar to that already described, so that the fingers 50^a rest on the flesh side of the sole and extend in between the loose fibers thereon, and, as the sole is fed, they will be carried into engagement with the reciprocating knife 52 and sheared off, as indicated in Fig. 5. The loose fibers will thus be sheared off close to the surface of the solid portion of the leather, and, as the cutter is permitted to swing vertically, and tilt, so that either end is higher than the other, the work-engaging faces of the fingers 50^a will 120 usually be held in engagement with the solid portions of the sole throughout the entire width of any portion which happens to be engaged. As there will be but slight resistance to the feeding action of the sole 130

after the sole has been inserted beneath the cutter, the sole will, in most instances, be fed automatically, but, the arrangement is such, that the operator may easily assist 5 the feeding action, if necessary.

It will be apparent from the foregoing description that the manner of operation does not substantially differ, whether the machine is used for removing the upper 10 from the sole, or for sole fleshing. All of the forms of cutters described, being adapted to operate without substantial resistance to the feeding action.

I claim—

15 1. In a machine for operating on shoe soles, a feed roll, a guard plate having a work-engaging face on its underside, supporting means adapted and arranged to hold said plate with its said face in approximately parallel relation to the elements of the roll surface and to permit movement of the plate to and from said surface, and spring actuated to move towards said surface, a knife supported by said 20 guard plate with its cutting edge in operative relation to the front edge of said face, means to operate said knife to move its cutting edge longitudinally of the axis of said roll, and means to rotate said roll to 25 feed the work to the knife.

2. In a machine for operating on shoe soles, a feed roll, a cutter comprising a guard plate movably supported in the rear of said roll and having a work-engaging 35 face on its under side, adjacent its front edge and in proximity to the roll surface, a knife reciprocally mounted on the upper side of said plate with its cutting edge in operative relation to the front edge of said 40 face, means for lifting said plate to permit the insertion of the work between said face and roll, yieldingly actuated means for pressing said plate downwardly, to hold said face against the work, means to reciprocate said knife in the different positions 45 in which it is adapted to be held, and means to drive said roll to feed the work towards the knife.

3. In a machine for operating on shoe 50 soles, a feed roll, a guard plate having a work-engaging face on its under side and extending from its front edge, pivotal supports for said plate in the rear of said roll arranged to hold said face in proximity to 55 the surface of the roll and to permit swinging movement thereof to and from said roll

in approximately parallel relation to the elements of its surface, manually controlled means for varying the vertical position of said plate, a knife carried by said plate 60 with its cutting edge adjacent the front edge of said plate, and means for reciprocating said knife longitudinally of said edge of said plate in the different positions thereof and means for rotating said roll to 65 feed the work to the knife.

4. In a machine for operating on shoe soles, a feed roll, a cutter comprising a lower guard plate having a sole engaging face on its under side at its front edge and 70 supported with its said face in approximately tangential relation to the roll surface, a knife reciprocally mounted on said plate with its cutting edge adjacent the front edge of said plate, an upper guard- 75 plate arranged above said knife and connected to said lower guard plate, means for lifting said cutter, to permit engagement of said face with the sole while resting on the roll and for yieldingly holding said face 80 against the sole and means to rotate the roll to feed the sole to the cutter.

5. A machine for operating on shoe soles comprising a feed roll, a movably mounted guard plate having a series of tapering fingers projecting from its front edge, means for yieldingly engaging the under sides of said fingers with the upper sides of a sole resting on said roll, a knife reciprocally mounted on the upper side of said plate 90 and formed to provide a series of projecting teeth arranged to operate in shearing relation with the sides of said fingers and means to reciprocate said knife as a sole is fed thereto by said feed roll. 95

6. A machine for operating on shoe soles comprising feeding means for engaging the under side of a sole and a cutter for operating on the upper side of a sole supported by said means, said cutter comprising a movably supported plate having a series of tapering fingers projecting from its front edge and adapted to rest on the upper sole surface adjacent their ends, a knife reciprocally mounted on said plate and having 105 a series of tapering blades movable in shearing relation with said fingers, spring actuated means for pressing said fingers against the sole and means to reciprocate said knife.

In testimony whereof, I have signed my 110 name to this specification.

CARL S. NORDEN.
